[57] CLAIM

The ornamental design for a combined rotisserie motor and light, as shown and described.

DESCRIPTION

FIG. 1 is a perspective view of a combined rotisserie motor and light showing my new design;

FIG. 2 is a top view thereof;

FIG. 3 is a front elevational view thereof;

FIG. 4 is a side view thereof;

FIG. 5 is a back elevational view thereof; and

FIG. 6 is a bottom view thereof.

The broken line disclosure of the knobs in FIGS. 2, 4, 5 and 6 is for illustrative purposes only and forms no part of the claimed design.

Fig. 1.

Fig. 2.

Fig. 3.

Fig. 4.

Fig. 5.

Fig. 6.
